W. W. DEAN

PHONOGRAPH CONTROLLING MECHANISM

Original Filed June 20, 1919

W. W. DEAN INVENTOR.

BY *Rickey, Slough & Tales*
His ATTORNEY'S

UNITED STATES PATENT OFFICE.

WILLIAM W. DEAN, OF LOWELL, MASSACHUSETTS, ASSIGNOR TO THE EFFICIENCY ELECTRIC CORPORATION, OF NEW YORK, N. Y., A CORPORATION OF NEW YORK.

PHONOGRAPH-CONTROLLING MECHANISM.

Original application filed June 20, 1919, Serial No. 305,527. Divided and this application filed February 25, 1922. Serial No. 539,323.

To all whom it may concern:

Be it known that I, WILLIAM W. DEAN, a citizen of the United States, residing at Lowell, in the county of Middlesex and 5 State of Massachusetts, have invented certain new and useful Improvements in Phonograph-Controlling Mechanisms; and I do hereby declare the following to be a full, clear, concise, and exact description of the 10 invention, such as will enable those skilled in the art to which my invention appertains to make and use the same.

My invention relates to motor governing devices, and more particularly to such governing devices as may be used in connection 15 with motors required to be operated at a constant speed, as, for instance, phonograph motors and the like, although I may employ the device of my invention wherever such a 20 device finds a use.

It has been previously proposed to control the speed of a motor, such as electric motors, for driving the turn-table of a phonograph, by centrifugally operated electric contacts, 25 the same controlling electric circuits adapted under the control of these centrifugally operated contacts to retard the speed of the motor, so that the motor cannot exceed a given predetermined speed which is substantially that speed required to actuate the 30 centrifugally operated contacts.

The object of the present invention is to provide an improved motor governor, of the weighted type, which is efficient and uniform 35 in operation, which is capable of being maintained in a given condition of adjustment and which is inexpensive to manufacture and which may be manufactured in large quantities with the uniformity of resultant product.

The object of the present invention is to provide a reed spring governor wherein the electrical contact carried by the reed is shifted in a line coincident with the axis of rotation 45 of the motor shaft, and which reed spring may be secured directly to the motor shaft without the necessity of providing a separate mount for the same.

Other objects of my invention, and the invention 50 itself will be made plainer to those skilled in the art to which my invention appertains by reference to the drawing accompanying this specification, and which

drawing shows a preferred embodiment of my invention.

Referring to the drawings—

Fig. 1 shows an embodiment of my invention partly in elevation and partly in section.

Fig. 2 shows a different form in which my 60 invention may be embodied.

Referring now to Fig. 1, at TN, I show a phonograph turn-table which is required to be driven by an electric motor M at a constant speed. The worm gear WG is interposed between the turn-table and the motor shaft SS so that the said shaft communicates motion to the said turn-table. A thrust spring S and thrust bearing TB is provided for the motor shaft to prevent longitudinal 70 displacement of the said shaft when the motor is operated. This spring may be formed by bending a flat leaf spring into the form of a loop and securing both ends by the machine screw 2, or by making the 75 spring in a single endless loop, as illustrated. The spring, however, will be made sufficiently thin for the purposes hereinafter set forth, and have sufficient width as to prevent distortion when the motor is operated to rotate the spring loop rapidly such as at a speed of substantially 1100 R. P. M., which speed I find to be a convenient one to use for the purpose of driving the turn-table TN.

At the other end of the loop and disposed in line with the axis of rotation of the shaft SS, is an electrical contact SC carried by the spring. Weights W¹ and W² are riveted to the spring LS on that side of the loop towards the supporting shaft SS, and at points on either side of the shaft SS, and between the shaft and the outer portions of the loop most distant from the axis of rotation thereof. When the motor is operated to drive the shaft SS to a predetermined speed which may be a speed of substantially 1100 R. P. M., the weights W¹ and W² under the action of centrifugal force, will deform the shape 95 of the loop in such a way that the side of the loop to which the electrical contact SC is secured, will be moved axially of the shaft SS, and in a direction away from the end of the said shaft, thus at a critical speed determined by the mechanical dimensions of the 100 spring LS and the weight thereof, and the 105

weight of the weights W^1 and W^2 , the contact SC carried by the spring will engage the stationary electric contact CE.

- When this occurs, an electrical circuit will 5 be completed bridging the electrical circuit conductors 3 and 4 which lead from a source of energizing current which may be an alternating or a direct current source, and which bridged circuit comprises the winding "W" 10 of the relay U, the contact seat comprising the contacts SC and CE, and the circuit conductors 7 and 8 leading from the mains 3 and 4 to the contact CE and the relay U respectively. 15 As long as this circuit is closed by the engagement of the contacts CE and SC, the relay U will attract its armature, breaking the contacts 9 which normally are bridged across the terminals of a resistance coil 10, 20 thereby introducing into the energizing circuit of the motor M, the resistance coil 10, to cut down the supply of current to the said motor. The relay U will preferably be of the quick acting type, and the motor energizing current being diminished by the breaking of the contacts 9, the speed at which the shaft SS is rotated will immediately be reduced, and the centrifugal force diminishing will cause a re-opening of the 25 contacts CE and SC substantially as set forth in my co-pending application Serial No. 297,621, filed May 16, 1919.

This application is a division of my application Serial No. 305,527, filed June 20, 35 1919.

As described above, the electrical contacts in the circuit of the relay U will be closed, and consequently immediately re-opened and at all times during the operation of the motor M there will be a continuous closing 40 and opening of these contacts, the relative length of time that the contacts are closed to the length of the periods during which they are opened determining the speed of 45 the motor M, and this may be varied by rotating the contact carrying adjusting screw AS to advance or withdraw the stationary contact CE.

I find that a governing centrifugal mechanism comprising a closed loop spring shaped substantially and operating as does the spring LS gives very uniform and continuously uniform results, and such a spring can be put into place on a rotating shaft, and 50 will function just as will such another spring manufactured at the same time and given substantially the same adjustment, and that uniformity of operation can be predetermined, which is not possible with other 55 types of governing springs having more than one point of support.

Referring now to the embodiment of my invention illustrated in Fig. 2—

Instead of the closed loop spring of Fig. 1, 60 I herein employ a loop spring which is sub-

stantially U-shaped, the spring carried contact SC being also axially disposed, but in this case I place the weight W on that arm of the U-shaped spring farthest away from the supporting shaft SS, so that the weight W, when operated upon by centrifugal force caused by the rotation of the shaft, will most efficiently move the contact in an axial direction. 70

Having thus described my invention in a 75 plurality of embodiments, I am aware that numerous and extensive departures may be made from the embodiments herein illustrated and described, but without departing from the spirit of my invention. 80

I claim:—

1. In an electric governing switch for controlling the speed of an electric motor, a pair of speed controlling switch contacts, a motor shaft carried loop reed spring carrying one of the said contacts substantially in line with the axis of rotation of the motor shaft, said spring being secured at a single point in said axial line and weight members secured to said loop spring in alignment with said shaft center, said one contact being movable outwardly from beyond the shaft end upon an increase of shaft rotational speed, the other contact being stationary and adapted to be engaged by said one contact. 90

2. In a switch for controlling the speed of an electric motor a looped reed spring carried on the end of a motor by being secured at a single point thereto and being rotatable thereby, a pair of switch contacts, one of said contacts being stationary and the other being carried on the said spring in line with the axis of rotation of the motor shaft and weights carried by said loop, said contact being movable axially upon changes in rotational speed, said spring carried contact moving outwardly axially from the shaft end upon an increase of speed to contact with the said stationary contact. 100

3. In a switch for controlling the speed of an electric motor, a stationary contact, a motor shaft, a closed loop spring carried on the end of the motor shaft being secured at a single point thereto and being rotatable thereby, a contact carried by said closed loop spring in line with the axis of rotation of the motor shaft, and weights carried by the spring, said movable contact being movable axially of the motor shaft upon changes of 105 rotational speed. 110

4. In a switch for controlling the speed of an electric motor, a stationary contact, a motor shaft, a closed loop spring carried on the end of the motor shaft being secured at a single point thereto and being rotatable thereby, a contact carried by said closed loop spring at a point opposite the point of support and axially of the supporting motor shaft, and weights carried by the spring, 120 125 130

said movable contact being movable axially of the motor shaft upon changes of rotational speed.

5. In a switch for controlling the speed of an electric motor, a stationary contact, a motor shaft, a closed loop spring carried on the end of the motor shaft being secured at a single point thereto and being rotatable thereby, a contact carried by said closed loop

spring at a point opposite the point of support and axially of the supporting motor shaft, and weights carried by the spring, said movable contact being movable axially outwardly of the motor shaft upon changes of rotational speed. 10

In witness whereof I have hereunto set my hand this 20th day of February, 1922.

WM. W. DEAN. 15
